Primary Examiner — Deanna L Fluegeman(74) *Attorney, Agent, or Firm* — Paul Y. Feng; The Eclipse Group LLP(57) **CLAIM**

The ornamental design for a touchless pointing device, as shown and described.

DESCRIPTION

FIG. 1 is a front perspective view of the touchless pointing device as mounted to a display device, showing the new design;

FIG. 2 is rear perspective view of the touchless pointing device as mounted to a display device from FIG. 1;

FIG. 3 is a front view of the touchless pointing device as mounted to a display device from FIG. 1;

FIG. 4 is a front elevational view of the FIG. 1 embodiment;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom view thereof.

The broken line showing of the display device in FIGS. 1-3 is included for the purpose of illustrating the environment of the claimed design and forms no part thereof.
